UNITED STATES PATENT OFFICE.

ALBERT LAVIGNE, OF BRUNSWICK, MAINE, ASSIGNOR TO THE STAFFORD COMPANY, OF READVILLE, BOSTON, MASSACHUSETTS, A CORPORATION OF NEW JERSEY.

LET-OFF MECHANISM FOR LOOMS.

1,310,398.

Specification of Letters Patent.

Patented July 15, 1919.

Application filed August 21, 1916. Serial No. 115,943.

To all whom it may concern:

Be it known that I, ALBERT LAVIGNE, a citizen of the United States, residing at Brunswick, in the county of Cumberland, 5 State of Maine, have invented a certain new and useful Improvement in Let-Off Mechanisms for Looms, of which the following is a specification, reference being had therein to the accompanying drawings.

10 The invention is an improvement in let-off mechanisms of what is termed the compensating class. Such mechanisms have a follower or presser which is arranged to bear against the periphery of the wound supply of warp-threads upon the warp-beam of a loom, etc. This part forms an element of provisions for regulating the rate of delivery of the warp-threads from said warp-beam so as to compensate for the progressive 15 decrease in diameter of the said supply as unwinding proceeds. Sometimes in practice in the weaving of certain classes of goods it is preferred to dispense with the compensating action and to operate with letting-off action of ordinary character. Moreover, 20 under some conditions the said follower is liable to interfere with certain of the manipulations or operations which are necessary to be performed by the weaver or loom- 25 fixer; for one thing, with the introduction of a filled warp-beam into place in the loom. It also is liable to swing, at the time of the 30 removal of a warp-beam from the loom, so as to strike upon some adjacent part of the 35 loom, as for instance the back girth, and become broken in consequence.

The general object of the invention is to provide means for enabling the compensating action to be superseded by ordinary letting-off action in the working of a loom, whenever required; in addition adapted to 40 enable such interference to be avoided, and for preventing the follower or presser from falling.

45 The invention consists, essentially in a follower-lock for locking the follower of a compensating let-off mechanism in stationary position whenever it is desired to supersede the compensating action or to effect a 50 removal or replacement of a warp beam. The invention admits of being embodied and applied in various ways. The drawings show in side elevation an embodiment of the invention applied in connection with 55 positive letoff devices of a well-known type,

the latter having combined therewith compensating devices of a character at present in use.

Figure 1 of the drawings is a side elevation of part of a loom, with the said embodiment applied thereto.

Fig. 2 shows a second embodiment.

In the drawings, which show only one of the forms of compensating let-off mechanisms to which the invention is applicable, 60 the follower or presser 1 is shown retracted and locked in a stationary position out of contact with the periphery of the wound mass 2 of warp-threads upon the warp-beam 3. Consequently the compensating 65 action has been superseded and in this condition the let-off mechanism will act as an ordinary let-off mechanism under the control of the tension of the warp, acting through the whip-roll 14 and the warp-beam 70 actuating devices and gearing controlled thereby. The warp-beam is in working position, with its journals 4 occupying bearings 5 in connection with the loom-frame, and with its gear 6 in mesh 75 with the beam-operating gearing 7 of the let-off mechanism. As usual the follower or presser is mounted with capacity 80 to swing toward and from the axis of the yarn-beam, and is adapted to be controlled 85 as to its position by the diameter of the wound mass of warp-threads upon the warp-beam. As usual, also, in operation it approaches the said axis in proportion as the 90 said diameter grows less by reason of the unwinding of the warp-threads. As herein shown, it is fixed upon a rockshaft 8 supported in convenient bearings in connection with the loom. The rockshaft 8 has a short, 95 arm 9 to which is joined one end of a link or connecting-rod 10, the other end of which is joined to an arm 11 in connection with the abutment 12 for the spring 13 by which the whip-roll 14 is controlled. The arm 11 and spring-abutment 12 are supported at 100 15 with capacity to rock or swing. The spring 13 surrounds a rod 16 having one end thereof joined to the whip-roll arm 14^a, and is confined under more or less compression between the said abutment and the said arm. 105 The said spring operates, as heretofore, to back up the whip-roll and also to keep the presser or follower close against the periphery of the mass of warp-threads wound upon the warp-beam. The rod 16 passes through 110

a hole in the spring-abutment 12 and has its other end joined to the controlling-lever 17 for the actuating pawl 18 of the let-off devices. As thus far described, the construction and operation, with and without the compensating action, are as heretofore.

In the embodiment of my invention that is shown in Fig. 1, I combine with the arm 11 and spring-abutment 12, in this instance, a 10 projection or tooth *a*, and a holding dog or detent *b* adapted to engage with said projection or tooth. The said projection or tooth projects from the hub of the spring-abutment, and the holding dog or detent is 15 mounted pivotally at *b'* in connection with the loom-frame. The projection or tooth and dog or detent preferably are so related that ordinarily they do not engage with each other during the ordinary working of 20 the parts, and consequently do not interfere with the movement of the spring-abutment and presser or follower which is necessary to take place in order that the presser or follower may remain in contact with the 25 surface of the wound mass of warp-threads upon the warp-beam as such mass becomes smaller in diameter. Or, the dog or detent may be swung back into an inoperative position, and remain in such position, out of the 30 way, until it is desired to act. It is intended that, as shown, the dog or detent shall be caused to engage with the projection or tooth when the presser or follower has been 35 swung by the weaver or loom-fixer away from the position of the warp-beam, and, through thus engaging, lock the presser or follower in a retracted inoperative position, as in Fig. 1, in which it will not be in the 40 way of a filled warp-beam which is being placed in position in the loom. Also, so that it will not fall when the warp-beam previously in the loom is removed, so as to land upon the back girth 19 with resulting 45 danger of breakage. Upon disengaging the dog or detent from the projection or tooth, the presser or follower will be freed, and the spring 13 will act through the spring-abutment and connections to the presser or

follower to move the latter into working engagement with the surface of the wound 50 supply of warp-threads upon the inserted warp-beam.

In the case of the embodiment shown in Fig. 2, the dog or detent *b*² is connected pivotally at *b'*² with the arm 11, and a stop-pin 55 *a*² is fixed upon the loom-frame. The parts are so related that when the follower or presser is swung back into its position in Fig. 1, the shoulder or engaging portion of the dog or detent *b*² will catch against the 60 stop-pin *a*² so as to hold the follower or presser in its retracted position. Ordinarily, however, the dog or detent will rest upon and play over the said stop-pin without engaging therewith, and without interfering 65 with the desired action of the follower or presser.

I claim as my invention:—

1. In a loom, the combination with warp-beam bearings, a warp-beam removably 70 mounted in the said bearings, and compensating let-off mechanism including a follower controlled as to its position by the changing diameter of the yarn-mass and itself controlling the rate of unwinding, of 75 a follower-lock for locking the said follower in a stationary position.

2. In a let-off mechanism for looms, the combination with a presser or follower making contact with the surface of the wound 80 supply of warp-threads upon the warp-beam, a spring-abutment connected with said presser or follower, and the whip-roll actuating spring acting through said abutment to press the presser or follower toward the 85 axis of the warp-beam, of a dog or detent adapted to coöperate with said spring-abutment to detain the presser or follower in a stationary position.

In testimony whereof I affix my signature 90 in presence of two witnesses.

ALBERT LAVIGNE.
